UNITED STATES PATENT OFFICE.

MARTIN L. NELSON, OF CHICAGO, ILLINOIS, ASSIGNOR TO AUTOMATIC ELECTRIC COMPANY, OF CHICAGO, ILLINOIS, A CORPORATION OF ILLINOIS.

PRIVATE-BRANCH-EXCHANGE SYSTEM.

Application filed July 9, 1917, Serial No. 173,827.

Renewed November 17, 1921. Serial No. 515,972.

To all whom it may concern:

Be it known that I, MARTIN L. NELSON, a citizen of the United States of America, and a resident of Chicago, county of Cook, and State of Illinois, have invented certain new and useful Improvements in Private-Branch-Exchange Systems, of which the following is a specification.

My invention relates to private branch exchange systems in general, but more particularly to exchanges of this character in which the subscribers establish connections themselves by means of automatic switching mechanisms, such an exchange constituting what is commonly known as a private automatic exchange, or P. A. X. These exchanges are usually installed in factories or business establishments of various kinds and, as in the embodiment herein disclosed, may consist of substations in each department and office of the establishment, and a switchboard comprising line or trunk selecting switches individual to the lines and a sufficient number of connector switches to handle the maximum number of simultaneous calls.

In an installation of this kind there are always a number of individuals, such as a general foreman or superintendent, for example, having duties of a supervisory nature which often take them on inspection trips through the different departments. Unless these trips are made in accordance with a regular schedule, which is seldom possible or even desirable, these individuals when so engaged will be bereft of telephone service so far as incoming calls are concerned. It is true of course, that an official by going to some trouble could notify his home station when he left for a different department and thus keep an attendant there posted as to his whereabouts; but this plan would be inconvenient, and by my invention no such cumbersome arrangement is required.

Briefly stated, the object of my invention is to provide a special code ringing and intercommunicating circuit whereby certain officials may be reached when they are absent from their offices on business in other departments. I provide a special bell in each department, all of which bells are connected in multiple across a common signaling circuit. Automatic code ringing equipment is provided adapted to close the common signaling circuit in accordance with predetermined codes, one of which is assigned to each

official to whom the special service is to be given. A certain set of contacts in the connector banks is to be used for the special signaling, and the telephone number associated therewith may be termed the special call number. A person who desires to communicate with an official who is temporarily absent in some unknown department will call the special call number, thereby extending a connection to the code ringing equipment. One or more additional digits are now called in order to set the ringing equipment for the code ring of the particular official wanted; whereupon all the special bells are rung in parallel in a distinctive manner which will be heard and recognized by the desired party wherever he happens to be. There is also a second set of bank contacts set aside for use in this connection, and upon perceiving his signal, the called party will turn to the nearest telephone and call the number corresponding to this second set of contacts, which I term the answer number. The two sets of bank contacts are tied together so that by this operation the calling and called parties will be telephonically connected. Conversation may be held over the circuit thus established; or in case an extended conversation is desired, one of the parties will give the other his telephone number, which may be called in the usual way, thereby freeing the code ringing equipment for use by someone else.

The foregoing is a brief statement of the object and scope of the invention. The preferred manner of carrying out the same, and the apparatus involved, will be described and explained fully hereinafter, reference being had to the accompanying drawings, which show the essential features of a private automatic exchange embodying the principles of the invention.

Fig. 1 shows diagrammatically the circuits of two substations associated with two connectors in a manner to best illustrate my invention.

Fig. 2 shows diagrammatically a code ringing equipment and the controlling circuit therefor, arranged to function properly with circuit of Fig. 1.

Referring to Fig. 1, the substation A may be of any suitable automatic type, such, for example, as the substation disclosed in British patent to Martin No. 1419 of 1910. As shown herein it consists essentially of a re-

ceiver 2, the transmitter 3, switch hook 4, ringer 5, and condenser 6. Being an automatic substation there is also provided a pair of impulse springs 7 and 8 which are controllable by the impulse wheel 9 through the medium of the finger hole dial (not shown).

The line conductors 12 and 13 terminate at the exchange in the individual line switch 10 C, which may be briefly described as a rotary line switch whose wipers have no normal position. A line switch of this character is shown in the patent to Lamb, No. 1,193,160 granted August 1, 1916. 15 The line switch C and a plurality of similar line switches may be given access to a group of trunk lines, each of which extends to and terminates in a connector switch. One of the trunk lines to which the line 20 switch C has access is shown in the drawing as terminating in the connector E, which may be of the general type of connector shown in Patent No. 815,176, granted March 13, 1906 to Keith, Erickson and Erickson. 25 The side switch and private magnet are omitted, however, and the circuits are modified in accordance with the two-wire system of control. These circuit changes, although forming no part of my invention, will be 30 explained fully hereafter during the description of the operation of the invention.

In the lower half of Fig. 1 I have shown a substation A', an individual line switch C', and a connector E', which are in all respects similar to the substation A and the switches C and E respectively.

It will be understood that the connectors E and E' are two of a group of connectors which are used for the purpose of interconnecting calling and called lines in the usual manner. The banks of all the connectors of the group are, of course, connected in multiple and form terminals of normal conductors extending to the individual line switches associated with the lines of the system. This multiplying of the banks is not shown in the drawings, but is understood to be in accordance with the usual practice. In brief, the private automatic exchange in 40 connection with which I have chosen to illustrate the invention, comprises a plurality of substations including the substations A and A', a plurality of individual line switches, such as the line switches C and C', and a 45 group of connectors accessible to all the line switches in common. A calling subscriber upon removing his receiver operates his individual line switch in order to select and extend connection to an idle connector 50 switch, and the selected connector is thereafter directly controlled to connect with the normal conductors associated with a desired called line.

It has been mentioned before that a certain set of contacts in the connector banks

is set aside for extending connection to the special code ringing equipment. While any set of contacts may be thus reserved, I prefer to use the last set in some particular level and in the following it will be assumed that the last set of contacts in the seventh level is reserved for this purpose. The special call number therefore, will be the number 70. In this connection attention should be called to the fact that each connector is provided with a set of special rotary off normal springs which, in the case of the connector E, are the springs 65, 66, and 67. The spring 67 is normally in engagement with spring 65 and is adapted to be shifted into engagement with spring 66 by the rotary cam 75 when the connector is operated in accordance with the number 70. There is also a set of contacts set aside for answering, to be called when a party is responding to his code ring, and it will be assumed that the contact set reserved for this purpose is the ninth set of contacts in the seventh level. It follows that the special answering number will be the number 79. Both sets of contacts are multiplied as usual through the group of connectors. In addition the contact set corresponding to the call number 70 is multiplied with the contact set corresponding to the answering number 79. This is shown in 95 the drawing as will now be pointed out.

The contact set associated with connector E, comprising bank contacts 93, 94, and 95, is the last or tenth contact set in the seventh level, while the contact set associated with connector switch E' is the ninth set of contacts in the seventh level. The line contacts 93 and 95 are connected by means of conductors 76 and 77 with line contacts 193 and 195. It will be observed that these conductors are transposed so that the upper line contact 93 is multiplied with the lower line contact 195, while the lower line contact 95 is multiplied with the upper line contact 193. The private or test contacts 94 and 194 are 110 not multiplied excepting, of course, for the usual multiple to corresponding contacts in the different connectors of the group.

From the test contacts 94 and 194 and the line contact 95, respectively, conductors 96, 115 97 and 98 extend to a group of relays which are indicated collectively by the reference character H, Fig. 2. These relays have the function of controlling the rotary switches M and N in a manner which will be described fully hereinafter. The rotary switch M may be termed a code selecting switch and comprises essentially a stepping magnet 113 and the four wipers 115 to 118, inclusive, with their associated sets of bank contacts. 120 The switch M may be similar in construction to the rotary line switch C, Fig. 1, although, of course, the circuits are altogether different because of the different operations which the switch has to perform. The ro- 130

5 tary switch N is similar to the rotary switch M but has only two wipers 119 and 120. The stepping magnet for the switch N is indicated by the numeral 114. The 10 switch N may be termed a ringing switch and its function is to close the common signaling circuit in accordance with the code selected by the switch M. This circuit is closed over the conductor 121 which extends 15 to the relay 122. When energized the relay 122 connects the generator Gen' across the conductors 123 and 124 which extend to all the offices or departments of the business establishment in which the system is installed. 20 As before explained, a signaling device or ringer is connected across these conductors in every department. Three of these ringers are shown in the drawings and are indicated by the reference characters R', R², and R³. 25 The bank wiring between the switches M and N will not be explained in detail just now, but will be described in the course of the description of the operation.

30 While I have shown throughout the drawings a plurality of batteries it will be understood that there is preferably but one battery having its positive pole grounded. In order not to encumber the drawings separate reference characters have not been applied to 35 the separate batteries, but it will be understood that when, in the description of the operation, a circuit is traced "to battery" it extends to the live or ungrounded pole of central battery. The busy signaling machine 40 Q and the intermittent ringing equipment I R shown in Fig. 1 are of the usual type common in other well known automatic exchanges.

45 Having given a brief description of the apparatus involved, I will now proceed to describe more in detail the operation of the system. For this purpose it will be assumed that the subscriber at substation A desires to communicate with an official X who is known to be temporarily absent from his office. Usually the subscriber at substation A will have ascertained this fact by calling X at his office in the usual manner. However, this is of no importance for it is sufficient for present purposes to assume that 50 X is at some unknown point in the establishment and that in order to communicate with him it will be necessary to use the special call system provided by my invention. 55 The subscriber at substation A will therefore remove his receiver and operate his calling device in accordance with the digits of the call number 70.

60 Upon removal of the receiver a circuit is completed for the line relay 15 of the line switch C as follows: ground at G', resting contact of armature 18 and said armature, line conductor 13, substation A, line conductor 12, armature 20 and its resting contact, and the winding of line relay 15 to

65 battery. Upon energizing, the line relay 15 completes the following circuit: ground at G², armature 21 and its working contact, winding of relay 16, interrupter contact of stepping magnet 17, and the winding of 70 said magnet to battery. Simultaneous with the close of the above circuit, the line relay connects the private or test wiper 31 to the junction point 24 as follows: test wiper 31, armature 19 and its resting contact, armature 22 and its working contact, to junction point 24. It is understood that the wipers of the line switch are normally in engagement with some contact set in the bank and the operation now depends upon whether 75 the contact set upon which the wipers are resting is busy or not. If this contact set is busy the test contact which is engaged by the test wiper 31 will have a ground potential upon it, resulting in the energization 80 of the stepping magnet 17 and the short circuiting of the relay 16. By the operation of the stepping magnet 17 the switch wipers are advanced to the next contact set, and since the stepping magnet interrupts its own 85 circuit, the advance of the wipers will be continued through the vibratory operation of the stepping magnet as long as the test wiper 31 continues to engage grounded or busy test contacts. When an idle or ungrounded test contact is reached, which we 90 will assume to be the test contact 34, the operation of the stepping magnet will cease, and the relay 16, being no longer short circuited, will be energized over the previously 95 described circuit extending from ground G². The resistance of relay 16 is sufficiently high 100 to prevent the stepping magnet 17 from energizing over this circuit.

105 By the operation of the relay 16 the test wiper 31 is connected to the winding of the said relay at its armature 19; and at its armatures 20 and 18 the line conductors 12 and 13 are disconnected, respectively, from the winding of the line relay 15 and from 110 ground G', and are extended by way of line wipers 30 and 32 and bank contacts 33 and 35 to the windings of the double wound line relay 40 of the connector E.

115 The line relay 40 is accordingly energized in the usual manner over the calling subscriber's loop, and completes the usual circuit for the slow acting release relay 41. Upon attracting its armatures, relay 41 prepares the usual circuit for the vertical and 120 rotary magnets 48 and 49 (at lower armature 52) and at its upper armature 78 closes a holding circuit for the relay 16 of line switch C, which may be traced as follows: ground at G³, working contact of armature 78 and the said armature, bank contact 34, test wiper 31, armature 19 and its working contact, winding of relay 16, and winding of magnet 17 to battery. A branch of the 125 above circuit extends from junction point 130

23 by way of private normal conductor 27 to multiple test contacts in the banks of the connectors where, by a ground potential on these test contacts, the line of substation A 5 is made busy.

The foregoing operations have occurred automatically in response to the removal of the receiver at substation A. The calling subscriber may now operate his calling device 10 in accordance with the first digit of the call number which is the digit 7. When the calling device is operated the impulse springs 7 and 8 are separated momentarily seven times, producing a corresponding series of 15 interruptions in the circuit of the line relay 40 of the connector E. In response to these interruptions of its circuit the line relay 40 is deenergized a number of times and at each deenergization transmits an impulse to the 20 vertical magnet 48 over the following path: ground at G⁴, armature 51 and its resting contact, armature 52 and its working contact, off normal springs 59 and 58, winding of the low resistance slow acting relay 42, 25 and the winding of the vertical magnet 48 to battery. In response to these impulses the vertical magnet is operated to raise the switch shaft step by step until the wipers 90, 91, and 92 stand opposite the seventh horizontal 30 level of bank contacts. The slow acting relay 42 is energized in series with the vertical magnet and retains its armature 53 attracted during the series of impulses, thereby preventing the opening of the vertical magnet circuit at the off normal springs 35 which are shifted as soon as the switch shaft leaves its normal position.

The calling subscriber may now call the 40 final digit of the special call number, which is the digit 0. As before, by momentary separations of the impulse springs 7 and 8, a series of interruptions is produced in the circuit of the line relay 40. Now, however, 45 the off normal springs being in the position shown in the drawing, and the relay 42 having deenergized, the line relay transmits a series of impulses to the rotary magnet 49, the circuit being as follows: ground at G⁴, armature 51 and its resting contact, armature 52 and its working contact, off normal 50 springs 59 and 57, armature 53 and its resting contact, winding of low resistance slow acting relay 45, resting contact of armature 52 and the same armature, armature 54 and its resting contact, and the winding of the 55 rotary magnet 49 to battery. The rotary magnet is operated in response to these impulses to rotate the switch shaft until the 60 wipers 90, 91, and 92 are brought to rest in engagement, respectively, with bank contacts 93, 94, and 95, which bank contacts comprise the tenth set of contacts in the seventh level. The slow acting relay 45 is 65 energized in series with the rotary magnet 49 and maintains its armatures continually

attracted during the rotation of the switch. At its lower armature 60 relay 45 disconnects the test wiper 91 from the lower winding of relay 46 and connects it instead by way of spring 70, resistance 47, and the 70 resting contact of armature 60 and said armature, to the upper winding of the combined test and answering bridge relay 43. The momentary energizations of relay 43 due to the test wiper 91 passing over busy or 75 grounded test contacts, if there be any such in its path, are of no consequence because of the alternative circuit for the rotary magnet by way of armature 68 of relay 45 and its working contact. The connector wipers having been rotated into engagement with the set of bank contacts corresponding to the special call number, the operation now depends upon whether the special code ringing equipment associated with that set of contacts is busy or not. In order to explain the 80 operation of the connector E in calling a busy line, it will first be assumed that the special ringing equipment is busy. Under 85 these circumstances, there will be a ground potential on the test contact 94 and when the connector wipers are rotated into engagement with bank contacts 93, 94, and 95, relay 45 being energized during the rotation as 90 before described, as soon as the test wiper 91 arrives at the test contact 94 the relay 43 will be energized over the circuit previously 95 traced with the following results: At the resting contact of armature 55 a contact in the circuit of the lower winding of relay 46 100 is opened and at the working contact of the same armature relay 43 prepares a locking circuit for itself which is completed upon the deenergization of relay 45 an instant later, and which extends as follows: ground at G³, working contact of armature 78 and the said armature, conductor 79, armature 55 and its working contact, contact point 71, spring 70, resistance 47, resting contact of 105 armature 60 and said armature, and the upper winding of the said relay 43 to battery. In addition, the circuit of the rotary magnet 49 is opened at the resting contact of armature 54 and at the working contact of armature 56, a lead from the busy signaling 110 machine Q is connected to the lower heavy line conductor in order to notify the calling subscriber that the attempted connection cannot be obtained. He will accordingly replace his receiver, whereupon the automatic switches C and E are restored to normal condition in a manner which will be hereinafter 115 described.

Having explained briefly how the connector E operated when a busy line is called, I will now return to where it was explained how in response to the final series of impulses the switch wipers were rotated on to the bank contact set corresponding to the 120 call number 70, and from this point the 125 130

regular operation will be proceeded with. If there is no ground potential upon the test contact 94, when the slow acting relay 45 deenergizes at the end of the final series of 5 impulses the following energizing circuit is completed for the switching relay 46: ground at G³, working contact of armature 78 and the said armature, conductor 79, armature 55 and its resting contact, lower 10 winding of relay 46, resting contact of armature 69 and the said armature, test wiper 91, test contact 94, conductor 96, armature 105 and its resting contact, and the winding of relay 102 to battery. Upon the closure of 15 the above circuit relays 46 and 102 are energized in series. As a result of the energization of the former relay at resting contact of armature 72 the circuit of the rotary magnet 49 is opened, and at the working contact of the same armature a circuit is prepared for the ring cut off relay 44. As a further result of its energization, relay 46 closes a contact in the lower heavy talking conductor at its armature 74, and at its 20 armature 73 short circuits its lower winding and completes a locking circuit for itself by way of its upper winding, the circuit being traceable as follows: ground at G³, working contact of armature 78 and the said armature, conductor 79, armature 73 and its two working contacts to the upper winding of the said relay 46 and to the test wiper 91. By the connection of direct ground to the test contact 94 and its multiples, the special ringing equipment is made busy in the banks of 25 the remaining connectors of the group. The operation of relay 102, Fig. 2, which it will be remembered was energized in series with the relay 46 of the connector, is without particular function just at this time.

The connection has now been extended to the trunk line terminating in the special ringing equipment shown in Fig. 2, and the apparatus is in readiness for the transmission 30 of setting impulses to code selector M. The calling subscriber is, of course, acquainted with the code ring which has been assigned to the wanted party X, and knows, also, what digit is now necessary to be called in order to operate the code selector M for 35 the purpose of selecting this particular code ring. We will assume that the code ring used for signaling X is one long and one short, and that the code selector M is so wired that in order to select this particular code ring, the digit five must be called. The calling subscriber will, therefore, operate his calling device in accordance with this digit, thereby producing as before, a series 40 of interruptions in the line circuit and a corresponding series of deenergizations of the line relay 40. These deenergizations of the line relay are at this time ineffectual to cause any further operation of the connector E for 45 the rotary magnet circuit has been opened, as before explained, at the resting contact of the armature 72. It has been explained before, however, that when the connector E is operated in accordance with the number 70 the rotary off normal springs 65, 66, and 67 70 are shifted, and since these springs, therefore, will now be in the position shown in the drawing, the deenergizations of the line relay now result in the transmission of a series of impulses to the stepping magnet 75 113 of the code selector M, the circuit being as follows: ground at G⁴, armature 51 and its resting contact, armature 52 and its working contact, off normal springs 59 and 57, armature 53 and its resting contact, rotary off normal springs 66 and 67, resting contact of armature 63 and the said armature, armature 74 and its working contact, wiper 92, bank contact 95, conductor 98, armature 106 and its resting contact, armature 108 and its resting contact, winding of low resistance slow acting relay 103, and the winding of the stepping magnet 113 to battery. Five impulses are transmitted to the stepping magnet 113 over the above circuit 80 85 and the switch wipers 115 to 118, inclusive, which normally rest in engagement with the first contacts in their respective banks, are advanced five steps to the position shown in the drawing. Relay 103 is energized in series with the stepping magnet 113 and being slow acting retains its armature during the series of impulses. At the end of the series of impulses relay 103 deenergizes and connects ground G⁶ to the wiper 115, thereby 90 closing an energizing circuit for the relay 101 as follows: ground G⁶, resting contact of armature 111 and the said armature, wiper 115 and the bank contact engaged thereby, conductor 134, and the winding of relay 101 100 to battery. Upon energizing, relay 101 prepares a circuit for the relay 100 at its armature 107 and at its armature 108 opens the circuit of the stepping magnet 113. A branch of the energizing circuit of relay 101 110 may be traced to relay 104 as follows: junction point 136, armature 110 and its working contact, interrupter contact of the stepping magnet 114 of ringing switch N, and the winding of the stepping relay 104 to 115 battery. Upon energizing, relay 104 completes an extension of the above traced branch as follows: junction point 137, armature 112 and its working contact, and the winding of stepping magnet 114 to battery. 120 The stepping magnet 114 is accordingly energized and by its operation the wipers 119 and 120 of the ringing switch N are advanced one step. Near the end of its stroke the magnet 114 opens the circuit of the stepping relay 104 which is thereupon deenergized and opens the circuit of the stepping magnet. A vibratory action is thus set up between the stepping relay 104 and the stepping magnet 114, whereby the wipers 119 130

and 120 are advanced step by step into engagement with successive contacts in their respective banks, and it will be evident that this operation will continue as long as a ground potential is maintained upon the junction point 137.

When on its second step the wiper 120 arrives at the contact 140 a circuit is completed for the relay 122 as follows: ground at G⁶, resting contact of armature 111 and the said armature, wiper 115 and the bank contact engaged thereby, conductor 133, wiper 120, bank contact 140, conductor 121, and the winding of the said relay 122 to battery. Upon energizing, relay 122 bridges the generator Gen¹ across the two conductors 123 and 124, thereby operating the ringers R', R², R³, and all other ringers similarly connected. When the wiper 120 reaches contact 141 on the third step the circuit of the relay 122 is not interrupted, but is maintained closed over the following path: grounded wiper 120 by way of bank contact 141, conductor 125, bank contact engaged by the wiper 118 and the said wiper, conductor 132, conductor 121, and winding of relay 122 to battery. Obviously, the above circuit will continue to be closed while the wiper 120 is passing bank contact 142. During the time that the wiper 120 is in engagement with the contact 143 the circuit of relay 122 is closed over the path originally described. While the wiper 120 is in engagement with contacts 144 and 145 the circuit of relay 122 is still maintained closed over the following path: grounded wiper 120, contact 144 or 145, conductor 126, contact engaged by the wiper 117 and the said wiper, conductor 132, conductor 121, and the line relay 122 to battery. It will be evident, also, that while the wiper 120 is in engagement with bank contact 146, the circuit will still be closed as originally. Thus it will be seen that the circuit of the relay 122 will be closed continuously while the wiper 120 is passing contacts 140 to 146, inclusive, thereby producing a long closure of the common signaling circuit. But while the wiper 120 is passing contacts 147 and 148 the circuit of the relay 122 is interrupted, for it will be seen when tracing the circuit that none of the contacts to which the conductor 127 is multiplied in the bank of the code selector M is engaged at this time by the wiper 116. The relay 122 is accordingly deenergized while the wiper 120 is passing contacts 147 and 148. When the contact 149 is reached the circuit of the relay 122 is again completed as originally described, and since the circuit is interrupted again upon the arrival of wiper 120 at contacts 150 and 151 the relay 122 is energized only momentarily to produce a short closure of the signaling circuit. As the wiper 120 continues its rotation and successively engages the remaining contacts in its

bank, it produces no further operations of the relay 122, as may be readily ascertained by tracing the circuit connections of the remaining contacts. After completing one revolution the wipers of the switch N immediately start on another, and it follows that the signaling operation just described will be repeated at intervals.

When the called party X hears one of the special bells ringing in accordance with his code he will step to the nearest telephone, which we will assume to be the substation A', and call the answering number 79. Upon the removal of the receiver at the substation A' the line switch C' is operated automatically the same as was described in connection with the line switch C to select and establish connection with a trunk line extending to an idle connector switch. Assuming that the selected connector is the connector E', when the calling device at substation A is operated in accordance with the digits of the number 79, the connector E' will be operated under control of its line relay 180 to raise and rotate its wipers 190, 191, and 192, until they come to rest in engagement with the bank contacts 193, 194, and 195, respectively. The connector E' operates precisely like the connector E, and therefore the manner in which the above connection is established will not be described in detail. When the slow acting relay 186 deenergizes at the end of the rotation, a circuit is completed for the switching relay 185 as follows: ground at G¹⁰, working contact of armature 181 and the said armature, conductor 182, armature 183 and its resting contact, lower winding of relay 185, resting contact of armature 179 and the said armature, test wiper 191, test contact 194, conductor 97, and the winding of relay 100 to battery. Relays 185 and 100 are energized in series on the closure of the above circuit and the energization of the former relay has the usual results among which may be mentioned the preparation of an energizing circuit for the ring cut off relay 187 at armature 178, and the grounding of test wiper 191, and the closure of a locking circuit through the upper winding of the said relay 185 at armature 184. The lower line wiper 192 is also connected at the working contact of armature 177, whereby an energizing circuit is completed for the ring cut off relay 44 of connector E as follows: ground at G¹¹ or G¹², depending on the position of the intermittent ringing equipment I R, generator Gen or the booster battery, conductor 176, rotary off normal springs 175 and 174, resting contact of armature 173 and the said armature, armature 177 and its working contact, wiper 192, bank contact 195, conductor 77, bank contact 93, wiper 90, lower winding of the ring cut off relay 44, working contact of armature 72 and the said armature,

armature 54 and its resting contact, and the winding of the rotary magnet 49 to battery. Upon the closure of the above circuit the ring cut off relay 44 is energized, the rotary magnet 49 remaining inoperative, and at its armature 61 completes a locking circuit for itself as follows: ground at G^s , working contact of armature 78 and the said armature, conductor 79, armature 61 and its working contact, and the upper winding of the said relay 44 to battery. As a further result of its energization relay 44 extends the upper and lower heavy talking conductors by way of its armatures 60 and 63 through to the line wipers 90 and 92, respectively. An energizing circuit for the ring cut off relay 187 of the connector E' may now be traced over the following path: ground at G^s , working contact of armature 78 and the said armature, conductor 79, armature 61 and its working contact, lower winding of relay 43, spring 62, armature 63, armature 74 and its working contact, wiper 92, bank contact 95, conductor 76, bank contact 193, wiper 190, lower winding of ring cut off relay 187, working contact of armature 178 and the said armature, armature 172 and its resting contact, and the winding of the rotary magnet 171 to battery. Current flow in the above circuit brings about the energization of relay 187 with results similar to those described in the case of the ring cut off relay 44 of connector E including the extension of the heavy talking conductors by way of armatures 188 and 173 to the wipers 190 and 192. The complete talking circuit between the substations A and A' has now been established. The transmitters at the two substations are supplied with talking current through the windings of the line relays 40 and 180, respectively, while the voice currents take the path shown in the heavy lines. The back bridge relays 43 and 170 which supply talking current to the called subscribers in ordinary connections will evidently be energized in series, but have no battery supplying function in a connection of this character. It will be seen that the automatic operation of the ring cut off relays in the two connectors is due to the transposition of the conductors 76 and 77 which has been before mentioned, and it may be stated that these conductors are reversed especially for this purpose.

Returning to the relay 100, Fig. 2, which, it will be recalled, was energized in series with the relay 185 of connector E' , the operation of this relay opens the circuit of the stepping magnet 113 at a new point, (armature 106), and also serves to disconnect the conductor 96 from the winding of relay 102 and connect it instead direct to ground at the working contact of armature 105. Relay 102 does not deenergize at once, however, but is held up temporarily over the

following circuit: ground at G^s , resting contact of armature 111, wiper 115 and the contact engaged thereby, conductor 133, wiper 119 of the rotary switch N and the contact engaged thereby, conductor 138, and the winding of relay 102 to battery. As soon as the switch N completes its revolution the above circuit will be broken, for the first contact of the bank associated with wiper 119 is not in multiple with the remaining contacts. Relay 102 is therefore deenergized with the following results: At the resting contact of armature 110 a circuit is completed for the stepping magnet 113 for the purpose of restoring the code selecting switch M to normal position, and at the resting contact of armature 109 an auxiliary energizing circuit is completed for the relay 100 in order to maintain this relay energized and the contact sets 70 and 79 busy in case the subscribers should hang up their receivers before the code selector M had reached its normal position. The circuit of the stepping magnet 113 mentioned above may be traced as follows: ground at G^s , resting contact of armature 111 and the same armature, wiper 115 and contacts engaged thereby, conductor 134, armature 110 and its resting contact, interrupter contact of the stepping magnet 113, and winding of said magnet to battery. Since the above circuit includes the interrupter contact of the stepping magnet, the said magnet will operate intermittently to advance the switch wipers step by step to complete the revolution, the operation of the stepping magnet ceasing only when the wiper 115 arrives at the first contact in its bank. When this has occurred the circuit of the stepping magnet has been opened in an obvious manner, and also the circuit of relay 101, this relay being deenergized to open the above mentioned auxiliary energizing circuit for relay 100.

Referring to the talking connection which has been established through the medium of the apparatus shown in Fig. 1, when a conversation is finished both parties will replace their receivers. At the replacement of the receiver at substation A the circuit of the line relay 40 is broken resulting in the deenergization of the line relay and also in the deenergization of the slow acting release relay 41. By this operation the circuit of the release magnet 50 is closed as follows: ground at G^s , armature 51 and its resting contact, armature 52 and its resting contact, lower off normal springs, and the winding of said release magnet 50 to battery. The operation of the release magnet is effective to restore the connector E to normal position in the usual manner, its circuit being broken by the off normal springs when the switch shaft reaches its lowest position. As a further result of the deenergization of the

release relay 41 ground G² is disconnected from the holding circuit extending back to the relay 16 of the individual line switch C. Relay 16 accordingly deenergizes to restore the circuit of the line switch to its normal condition. The connector E' and line switch C' are released in the same manner as a result of the replacement of the receiver at the substation A'. All of the apparatus involved in the connection has now been restored to normal in readiness for other words.

In view of the preceding explanation it is believed that the operation of the code selector M and the ringing switch N in signaling in accordance with the other codes will be understood without going any further into details. While a variety of wiring schemes may be used for selecting the various code rings, the one which has been worked out is comparatively simple and is appended below in the form of a table for the benefit of those who may wish to practice the invention:

Call number.	Signal code.
30 701	1 long
702	2 long
703	4 short
704	5 short
35 705	1 long and 1 short
706	1 short and 1 long
707	1 long and 2 short
708	1 long and 3 short
709	1 long, 1 short and 1 long
40 7001	2 short and 1 long
7002	3 short and 1 long
7003	1 short, 1 long and 1 short
7004	1 short, 1 long and 2 short
7005	2 short, 1 long and 1 short
45 7006	1 short and 2 long
7007	2 long and 1 short
7008	1 long and 4 short
7009	4 short and 1 long
50 70001	3 short, 1 long and 1 short
70002	2 short, 1 long and 2 short
70003	1 short, 1 long and 3 short
70004	6 short

It will be observed that certain of the 55 call numbers appearing in the above table require the calling of either two or three digits instead of one in order to control the set of the code selector M. To provide for this, the 11th and 21st contacts in the bank 60 associated with the wiper 115 are not multiplied with the remaining contacts so that when the code selector is operated in accordance with the digit 0, for example, when the slow acting relay 103 deenergizes 65 at the end of the series of impulses, the ring-

ing switch N will not begin its operation. If the next digit called is some digit other than 0 at the end of the series of impulses the ringing switch N will be started as previously described for all contacts between the 11th and 21st are multiplied with the ones preceding the 11th. If the next digit called is again 0, however, the wiper 115 will be advanced to the 21st contact, making it necessary to call still another digit 75 before the ringing operation will begin. The switch is prevented from stopping on the 11th and 21st contacts during the release by means of a conductor 135 which serves when relay 102 is deenergized to join these two 80 contacts to the remaining ones.

Having described my invention, what I consider to be new and desire to have protected by Letters Patent will be pointed out in the appended claims:

What I claim as my invention is:

1. In a telephone system, a pair of connected terminals common to the exchange, means whereby a calling subscriber can obtain a connection with the first of said terminals, other terminals multiplied to said first terminals, and means for making said terminals busy when said calling subscriber obtains connection with said first terminal, signaling means associated with said first terminals for signaling a called subscriber, and means whereby the called subscriber can obtain a connection with the second of said terminals while said other terminals are busy, whereby the said calling and called subscribers may be telephonically connected.

2. In a telephone system, a pair of connected terminals common to the exchange, telephone call and answer numbers assigned to said terminals, respectively, means operated in accordance with the call number for connecting a calling subscriber with one of said terminals and for making said terminal busy when said calling subscriber obtains connection thereto, means for signaling the called subscriber, and means operated in accordance with the answering number for connecting the called subscriber with the other of said terminals while said first terminal is busy, whereby said subscribers may be telephonically connected.

3. In a telephone system, a pair of connected terminals common to the exchange, telephone call and answer numbers assigned to said terminals, respectively, means operated in accordance with the call number for connecting a calling subscriber with one of said terminals and for making said terminal busy when said calling subscriber obtains connection thereto, means for signaling the called subscriber in accordance with a pre-determined code, and means operated in accordance with the answering number for connecting the called subscriber with the 120

other of said terminals while said first terminal is busy, whereby said subscribers may be telephonically connected.

4. In a telephone system, a pair of connected terminals common to the exchange, automatic switching mechanism controlled by a calling subscriber for establishing connection with the first of said terminals, other terminals multiplied to said first terminals, and means for making said terminals busy when said calling subscriber obtains connection with said first terminal, signaling means associated with said first terminal for signaling a called subscriber, and automatic switching mechanism controlled by the called subscriber for establishing a connection with the second of said terminals while said other terminals are busy, whereby the said calling and called subscribers may be telephonically connected.

5. In a telephone system, a pair of connected terminals common to the exchange, telephone call and answer numbers assigned to said terminals, respectively, automatic switching mechanism controllable by a calling subscriber in accordance with the call number for extending a connection to one of said terminals and for making said terminal busy when said calling subscriber obtains connection thereto, means for then signaling the called subscriber, and automatic switching mechanism controlled by the latter in accordance with the answering number for extending a connection to the other of said terminals while said first terminal is busy, whereby the calling and called subscribers may be telephonically connected.

6. In a telephone system, a pair of connected terminals common to the exchange, telephone call and answer numbers assigned to said terminals, respectively, automatic switching mechanism controllable by a calling subscriber in accordance with the call number for extending a connection to one of said terminals and for making said terminal busy when said calling subscriber obtains connection thereto, a common signaling system and means for operating the same in accordance with a predetermined code to signal a called subscriber, and automatic switching mechanism controlled by the latter in accordance with the answering number for extending a connection to the other of said terminals while said first terminal is busy, whereby the calling and called subscribers may be telephonically connected.

7. In a private branch exchange system, a plurality of special signals located at different points in the system, a common circuit for actuating all said signals simultaneously in order to notify a party at some unknown point that he is wanted, means for bringing said circuit under the control of the calling subscriber, means controlled by the subscriber for determining the code by

which said signals are to be operated, and automatic means for thereafter causing said signal to be actuated in accordance with the predetermined code.

8. In a private branch exchange system, a plurality of special signals located at different points in the system, a common circuit for actuating all said signals simultaneously in order to notify a party at some unknown point that he is wanted, means under control of the calling subscriber for controlling said circuit in a predetermined distinctive manner to signal the particular party wanted and automatic means for thereafter actuating said signals in said predetermined manner.

9. In a private branch exchange system, a plurality of special signals located at different points in the system, a common circuit for actuating all said signals simultaneously in order to notify a party at some unknown point that he is wanted, means controlled by the calling party for preparing a talking circuit, and for thereafter closing said signaling circuit, and means controlled by the called party in response to the signal for completing said talking circuit and for opening said signaling circuit.

10. In a private branch exchange system, a plurality of special signals located at different points in the system, a common circuit for actuating all said signals simultaneously in order to notify a party at some unknown point that he is wanted, a code selector switch and a controlling switch, means under control of the calling party for setting said code selector to signal the particular party wanted, and circuit connections whereby said controlling switch is operated automatically thereafter to close said signaling circuit in accordance with the selected code.

11. In a private branch exchange system, a common signaling circuit comprising a plurality of signaling devices, equipment comprising a code selector and a controlling switch, automatic switching mechanism controlled by a calling subscriber in accordance with the digits of a special call number for extending a connection to said equipment, and means for then setting said code selector in accordance with another digit, the said controlling switch being automatically responsive to the setting of said code selector for closing said signaling circuit in accordance with the selected code.

12. The method of connecting calling and called subscribers in conversation in an automatic telephone system, which consists of the operation of an automatic switch by a calling subscriber to connect with one of a pair of terminals accessible to the subscriber and starting the operation of a code signalling equipment associated therewith to signal the called subscriber, and in the operation of automatic

- switches by the called party in response to the signal to connect with the other of said pair of terminals and thereby automatically stop the operation of said code signaling equipment and complete the connection between the calling and called subscribers.
13. In a telephone system, a pair of connected terminals common to the exchange, means whereby a calling subscriber can obtain a connection with the first of said terminals, signalling means associated with the first of said terminals for signalling a called subscriber, means whereby the called subscriber can obtain a connection with the second of said terminals whereby the calling and called subscribers may be telephonically connected, and automatic means responsive to the establishment of said telephonic connection for disconnecting said signalling means.
14. In a telephone system, a pair of connected terminals common to the exchange, telephone call and answer numbers assigned to said terminals, respectively, means operated in accordance with the call number for connecting a calling subscriber with one of said terminals, means for signalling the called subscriber in accordance with a predetermined code, means operated in accordance with the answering number for connecting the called subscriber with the other of said terminals whereby said subscribers may be telephonically connected, and automatic means responsive to the establishment of said telephonic connection for disconnecting said signalling means.
15. In a telephone system, a pair of connected terminals common to the exchange, automatic switching mechanism controlled by a calling subscriber for establishing a connection with the first of said terminals, signalling means associated with said first terminals for signalling the called subscriber, automatic switching mechanism controlled by the called subscriber for establishing a connection with the second of said terminals, whereby the said calling and called subscribers may be telephonically connected, and automatic means responsive to the establishment of said telephonic connection for disconnecting said signalling means.
16. In a telephone system, telephone lines, a pair of connected terminals common to the exchange, automatic switching mechanism controlled from a calling one of said lines for establishing connection with the first of said terminals, code signalling means associated with said first terminals, an automatic switch associated with said first terminals, means controlled from said calling line for operating said automatic switch to select a particular code in order to signal a subscriber at an unknown point in the exchange, and automatic switching mechanism controlled by the said called subscriber for

establishing a connection with the second of said terminals, whereby said calling and called subscribers may be telephonically connected.

17. In a telephone system, telephone lines, a pair of connected terminals common to the exchange, automatic switching mechanism controlled from a calling one of said lines for establishing connection with the first of said terminals, code signalling means associated with said first terminals, an automatic switch associated with said first terminals, means controlled from said calling line for operating said automatic switch to select a particular code, signals common to the exchange, means for operating said common signals in accordance with the selected code to signal a subscriber at an unknown point in the exchange, and means controlled by the said called subscriber for establishing a connection with the second of said terminals whereby said calling and called subscribers may be telephonically connected.

18. In a telephone system, a pair of connected terminals common to the exchange, automatic switching mechanism controlled by a calling subscriber for establishing connection with the first of said terminals, code signalling means associated with said first set of terminals, means controlled by said calling subscriber for selecting a particular code, a plurality of signals common to the exchange, automatic means for actuating said signals in accordance with the selected code to signal a called subscriber, and automatic switching mechanism controlled by the said called subscriber for connecting with the second terminals, whereby said calling and called subscribers are telephonically connected.

19. In a telephone system, a pair of connected terminals common to the exchange, automatic switching mechanism controlled by a calling subscriber for establishing connection with the first of said terminals, code signalling current associated with said first terminals, a code selecting switch accessible from said first set of terminals, mean controlled by said calling subscriber for operating said code selecting switch to select a particular code, signalling devices common to the exchange, automatic means for actuating said devices in accordance with the selected code, and means controlled by a called subscriber for obtaining connection with the other set of terminals thereby establishing a telephonic connection with said calling subscriber.

20. In a telephone system, a pair of connected terminals common to the exchange, automatic switching mechanism controlled by a calling subscriber for establishing connection with the first of said terminals, code signalling current associated with said first terminals, a code selecting switch accessible

- from said first set of terminals, means controlled by said calling subscriber for operating said code selecting switch to select a particular code, signalling devices common to the exchange, automatic means for actuating said devices in accordance with the selected code, means controlled by a called subscriber for obtaining connection with the other set of terminals thereby establishing a telephonic connection with said calling subscriber, and automatic means responsive to the establishment of said telephonic connection for stopping the operation of said signaling devices.
- 15 21. In a telephone system, a pair of connected terminals common to the exchange, automatic switching mechanism controlled by a calling subscriber for establishing connection with the first of said terminals, code signalling current associated with said first terminals, a code selecting switch accessible from said first set of terminals, means controlled by said calling subscriber for operating said code selecting switch to select a particular code, signalling devices common to the exchange, automatic means for actuating said devices in accordance with the selected code, means controlled by a called subscriber for obtaining connection with the other set of terminals thereby establishing a telephonic connection with said calling subscriber, and automatic means responsive to the establishment of said telephonic connection for stopping the operation of said signaling devices and for releasing said code selecting switch.
22. In a telephone system, a pair of connected terminals common to the exchange, automatic switching mechanism controlled by a calling subscriber for establishing connection with the first of said terminals, code signalling current associated with said first terminals, a code selecting switch accessible from said first set of terminals, means controlled by said calling subscriber for operating said code selecting switch to select a particular code, signalling devices common to the exchange, automatic means for actuating said devices in accordance with the selected code, means controlled by a called subscriber for obtaining connection with the other set of terminals thereby establishing a telephonic connection with said calling subscriber, and automatic means responsive to the establishment of said telephonic connection for releasing said code selector.
23. In a telephone system, two sets of connected terminals common to the exchange, automatic switching mechanism controlled by a calling subscriber for extending a connection to one of said sets of terminals, a source of code signalling current, a code selector accessible from said first set of terminals, means controlled by the said calling subscriber for operating said code selector to select a particular code, signalling devices common to the exchange, automatic means for operating said signalling devices in response to the selected code to signal a called subscriber, automatic switching mechanism controlled by the called subscriber for extending a connection to said second set of terminals whereby the calling and called subscribers are telephonically connected, and automatic means responsive to the establishment of the last connection for releasing said code selecting switch.
24. In a code ringing machine, a pair of step by step switches, permanent conductors connecting the bank contacts of one switch with the bank contacts of the other, ringing mechanism, subscriber controlled means for operating one of said switches to select a desired code, and automatic means for operating the other of said switches to operate said ringing mechanism in accordance with the selected code.
25. In a telephone system, a signalling circuit, a plurality of signals connected to said circuit, a code selecting switch operable by a calling subscriber to select a code, mechanism cooperating with said switch for operating said signals over said circuit according to the code selected, and means for preventing the restoration of said switch and cooperating mechanism in case the calling subscriber hangs up his receiver before the code is finished.
26. In a telephone system, a signalling circuit, a plurality of signals connected to said circuit, a code selecting switch operable by a calling subscriber to select a code, mechanism cooperating with said switch for operating said signals over said circuit according to the code selected, means for restoring said switch and cooperating mechanism controlled by the calling subscriber, and means for preventing the calling subscriber from producing a false signal by restoring said switch and cooperating mechanism before the code is completed.
27. In a telephone system, a signalling circuit, a plurality of signals connected to said circuit, a code selecting switch operable by a calling subscriber to select a code, mechanism cooperating with said switch for operating said signals over said circuit according to the code selected, means controlled by a called subscriber for stopping the signalling operation, and means for preventing the stopping of the signalling operation before the code is finished.
28. In a telephone system, a signalling circuit, a plurality of signals connected to said circuit, a code selecting switch operable by a calling subscriber to select a code, a sending switch cooperating with said selecting switch to operate said signals over said

circuit in accordance with the code selected, an operating circuit for said sending switch initially closed by the calling subscriber, and locking means for preventing the opening of 5 said circuit until the code is completed.

29. In a telephone system, a signalling circuit, a plurality of signals connected to said circuit, a code selecting switch operable by a calling subscriber to select a code, a 10 sending switch cooperating with said selecting switch to operate said signals over said circuit in accordance with the code selected, subscriber controlled means for restoring 15 said selecting switch, and means for preventing the restoration of said selecting switch while said sending switch is in an off normal position.

30. In a telephone system, a signalling circuit, a plurality of signals connected to said 20 circuit, a code selecting switch operable by a calling subscriber to select a code, a sending switch cooperating with said selecting switch to operate said signals over said circuit in accordance with the code selected, means 25 controlled by the called subscriber for stopping the signalling operation, and means for preventing the stopping of the signalling operation while said sending switch is in an off normal position.

31. In a telephone system, a signalling circuit, a plurality of signals connected to said circuit, a code selecting switch operable by a calling subscriber to select a code, a sending switch cooperating with said selecting switch to operate said signals over said circuit in accordance with the code selected, automatic means for operating said sending switch continuously to repeat the code at 35 intervals, ring-cut-off mechanism controlled 40 by the called subscriber, and means for rendering said mechanism ineffective except in the interval between the completion of one code and the starting of the next.

32. In a code ringing machine, a register 45 switch adapted to be set in accordance with a code digit, a code ringing switch controlled by said register switch, and means for preventing the restoration of said register switch except when said ringing switch is in 50 normal position.

33. In a code ringing machine, a register switch adapted to be set in accordance with a code digit, a rotary switch for transmitting 55 the code, means for operating said rotary switch continuously to repeat the code at intervals, and means for preventing the restoration of said register switch ex-

cept when the said rotary switch is in a particular position.

34. In a telephone system, a pair of terminal sets common to the exchange, unlike 60 call and answer numbers assigned to said sets, respectively, automatic switching mechanism controlled by a calling subscriber in accordance with the call number for connecting with the first of said sets, automatic 65 switching mechanism controlled by the called subscriber in accordance with the answer number for connecting with the second of said sets, and conductors connecting said terminal sets to permit conversation 70 between said subscribers.

35. In a telephone system, a plurality of 75 automatic switches, a set of multiply connected calling terminals in each of said switches having a call number, a set of multiply connected answering terminals in each 80 of said switches having an answer number, means under the control of a calling subscriber for operating one of said switches in accordance with the call number to connect with a set of calling terminals, means under the control of the called subscriber for operating another of said switches in accordance with the answer number to connect with a set of answering terminals, and multiple 85 connections between the calling and answering terminal sets to permit conversation between said subscribers.

36. In a telephone system, a pair of terminal sets common to the exchange, an automatic connector switch operable by a calling subscriber for connecting with the first of said terminal sets, a second automatic connector switch operable by the called subscriber for connecting with the second of said terminal sets, a back bridge relay in each connector bridged across the wipers thereof in series with the exchange battery, and transposed conductors connecting said 90 terminal sets whereby said relays are energized in series.

37. The combination, with a register switch adapted to be set in accordance with a digit in a number, of a code sending switch, automatic operating means for said second switch, and conductors connecting bank contacts of said register switch with bank contacts of said sending switch, whereby the code sent out is in accordance with the setting of said register switch.

Signed by me at Chicago, Cook County, Illinois, this second day of July, 1917.

MARTIN L. NELSON.
